(57) **CLAIM**

We claim the ornamental design for a display framework hub connector plate, as shown and described.

DESCRIPTION

FIG. 1 is a perspective view of a display framework hub connector plate;

FIG. 2 is a top plan view thereof;

FIG. 3 is a bottom plan view thereof; and,

FIG. 4 is an environmental perspective view thereof.

Dashed lines indicate structure that is not part of the claimed design.

The broken line showing is for illustrative purposes only and forms no part of the claimed design.
